(57) **CLAIM**

The ornamental design for a light emitting diode, as shown and described.

DESCRIPTION

FIG. 1 is a front top side perspective view of a light emitting diode in accordance with an embodiment of my new design; FIG. 2 is a front elevational view of the light emitting diode in accordance with the embodiment of my new design;

FIG. 3 is a rear elevational view of the light emitting diode in accordance with the embodiment of my new design;

FIG. 4 is a top plan view of the light emitting diode in accordance with the embodiment of my new design;

FIG. 5 is a bottom plan view of the light emitting diode in accordance with the embodiment of my new design; and,

FIG. 6 is a vertical center cross sectional view of the light emitting diode in accordance with the embodiment of my new design taken along line 6—6 in FIG. 4.

The broken line showing of environment (the remaining structure of the light emitting diode) in the Figures is for illustrative purposes only and forms no part of the claimed design.
